UNITED STATES PATENT OFFICE.

WILLIAM JASPER HINTON, OF DANVILLE, ILLINOIS.

TROLLEY-FINDER.

No. 823,832.

Specification of Letters Patent.

Patented June 12, 1906.

Application filed August 16, 1905. Serial No. 274,444.

To all whom it may concern:

Be it known that I, WILLIAM JASPER HINTON, a citizen of the United States, residing at Danville, in the county of Vermilion and State of Illinois, have invented new and useful Improvements in Trolley-Finders, of which the following is a specification.

My invention relates to trolley-finders; and its primary object is to provide a novel and highly-useful device of this character which may be applied to any construction of trolley-pole and which is so constructed that parts thereof may be replaced to obviate the necessity of supplying an entirely new finder should any part of the finder in use become broken and unfit for further service.

With the above and other objects in view the invention consists in the construction, combination, and arrangement of parts hereinafter fully described, claimed, and illustrated in the accompanying drawings, wherein—

Figure 1 is a side elevational view of a trolley-pole provided with a finder constructed in accordance with my invention, illustrating the manner in which the trolley-wheel is guided into contact with the trolley by means of my improved finder. Fig. 2 is an enlarged detailed perspective view of the upper portion of the trolley-pole and a fragmentary portion of the trolley, further illustrating the manner in which the trolley-wheel is guided into contact with the trolley by means of the finder. Fig. 3 is a side elevational view of that portion of the device illustrated in Fig. 2 on a reduced scale and illustrating the trolley-wheel in contact with the trolley and the position assumed by the finder, and Fig. 4 is a sectional view on the line 4-4 of Fig. 1.

Referring to the drawings by reference-numerals, 1 designates a trolley-pole, 2 a harp secured thereto, and 3 the trolley-wheel, journaled on the harp by means of a pintle 4, all being of the usual form and construction, except that the ends of the pintle 4 project laterally beyond the sides of the harp 2.

Elbow-bearing brackets 5 are provided with bearings 6, adapted to loosely receive the projected ends of the pintle 4, whereby the brackets are journaled upon the harp 2. The elbow-bearing brackets 5 consist of arms 7 and 8, and the bearings 6 are positioned at the points of the union of said arms. The arms 7 are recessed, as at 8^a, for the recep-

tion of the ends of a wire-engaging member 9, which is held in applied position upon the elbow-bearing brackets by means of threaded bolts 10, let through the arms 7 and engaging the ends of the wire-engaging member 9. 60 Should the wire-engaging member 9 become broken and distorted, and thereby rendered unfit for further use, it can be quickly replaced by a new member in a manner that is apparent. This member is constructed from 65 a single strand of wire or any suitable material and is bent intermediate its ends to provide two laterally-diverging arms 11, the connecting portion of which is positioned in alinement with the groove of the trolley-wheel 3. After the wire strand is bent to provide the arms 11 it is then bent in reverse direction downwardly in approximately parallel alinement with the arms 11 to provide supporting-arms 12, which have their lower 70 ends offset, as at 13, and positioned in the recesses 8 of the arms 7. The ends of the arms 8 are also recessed and adapted to receive the extremity of a yoke 14, said yoke being adapted to be removably secured to the arms 80 8 by means of threaded bolts 15, let through the arms and engaging the ends of said yoke, whereby to permit the yoke to be removed and replaced should it become broken or distorted, and thus rendered unfit for further 85 use. A cable 16 has one of its ends secured to the yoke 14 and its other end disposed in convenient reach, whereby the trolley-pole 1 may be moved to withdraw the trolley-wheel 3 from contact with the trolley or to position 90 the wire-engaging member to guide the trolley-wheel 3 into contact with the trolley.

The trolley-pole 1 is yieldingly supported by the usual spring, whereby to retain the trolley-wheel 3 in contact with the trolley. 95 It often occurs that during the movement of the car the trolley-wheel will slip the trolley, and to assist in directing the trolley-wheel into contact with the trolley again I provide the finder just described, and the manner in 100 which the same accomplishes the purpose for which it is intended may be briefly stated as follows: Should the trolley-wheel slip the trolley, the trolley-pole will assume a vertical position, and to move the pole so as to bring 105 the trolley-wheel beneath the trolley the cable 16 is brought into use. During this downward movement of the trolley-pole the yoke 14 and diverging arms 12 will prevent the trolley-wheel from coming into contact 110

with the trolley. After the trolley-wheel is positioned beneath the trolley the wire-engaging member is moved so as to position the trolley between the guide-arms 11, and upon 5 the releasing of the cable 16 the normal tendency of the trolley-pole to assume a vertical position will cause the trolley-wheel to move upward. Through virtue of the wire-engaging member said trolley-wheel will be guided into engagement with the trolley, after which 10 the finder will assume the position illustrated in Fig. 3, whereby the wire-engaging member is held in such position as not to form an obstruction—that is, it will not engage the 15 cross-wires usually used for supporting the trolley.

Changes in the form, proportions, and minor details of construction may be made within the scope of the invention without deviating from the spirit or sacrificing any of 20 the advantages thereof.

Having fully described and illustrated my invention, what I claim is—

In a device of the character described, the combination with a trolley-pole and a trolley-wheel journaled thereon, of elbow-bearing brackets journaled upon the trolley-pole and having their ends provided with recesses, a wire-engaging member detachably having its ends fitting in two of said recesses and a yoke having its ends fitting in the other two of said recesses, and bolts carried by the arms and engaging the ends of the wire-engaging member and yoke to removably secure them to the brackets.

In testimony whereof I affix my signature in presence of two witnesses.

WILLIAM JASPER HINTON.
